UNITED STATES PATENT OFFICE.

JAMES P. DUNNE, OF CHICAGO, ILLINOIS.

DESIGN FOR AN IMAGE OR DOLL.

50,185.

Specification for Design.

Patented Jan. 16, 1917.

Application filed May 22, 1916. Serial No. 99,240. Term of patent 3½ years.

To all whom it may concern:

Be it known that I, JAMES P. DUNNE, a citizen of the United States, residing at Chicago, in the county of Cook and State of Illinois, have invented a new, original, and ornamental Design for an Image or Doll, of which the following is a specification, reference being had to the accompanying drawing, forming part hereof.

Figure 1 is a view in front elevation of the image or doll, showing my new design. Fig. 2 is a view in side elevation of the image or doll, showing my new design.

I claim:

The ornamental design for an image or doll, as shown.

JAMES P. DUNNE.
